UNITED STATES PATENT OFFICE.

JAMES D. MOORE, OF NORTHWILKESBORO, NORTH CAROLINA.

SEPARATOR.

1,258,354.

Specification of Letters Patent. Patented Mar. 5, 1918.

Application filed July 6, 1915. Serial No. 38,215.

To all whom it may concern:

Be it known that I, JAMES D. MOORE, a citizen of the United States, residing at Northwilkesboro, in the county of Wilkes 5 and State of North Carolina, have invented a new and useful Separator, of which the following is a specification.

This invention relates to separators designed for use in the separation of grits from bran and meal, one of the objects of the invention being to provide a single blower and separate flues receiving air therefrom, means being employed whereby currents of different velocities are directed through the 10 respective flues to different parts of the apparatus so that bran can be separated from the grits without losing the fine grits.

A further object is to provide agitating means of novel form for preventing meal 20 from lodging in the separator screen and interfering with the proper operation of the machine.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, can be made within the scope of what is claimed, without departing from the spirit of the invention.

In the accompanying drawings the preferred form of the invention has been shown.

35 In said drawings:—

Figure 1 is a vertical longitudinal section through the separator.

Fig. 2 is a top plan view, certain of the parts being broken away.

40 Fig. 3 is a section on line A—B Fig. 1.

Fig. 4 is a side elevation of a portion of the machine.

Referring to the figures by characters of reference 1 designates standards connected 45 by cross beams 2 and by side beams 3, each side beam having a longitudinal inwardly extending flange 4 constituting a guide or spacing element. One of the beams 3 is enlarged from top to bottom at one end, as 50 shown at 5, this enlarged portion being provided with a large opening 6.

Pivottally connected to and suspended from the upper portion of each of the standards or posts 1 is a hanger 7 and these 55 hangers are all pivotally connected to the sides of a sieve box 8 provided, near one

end, with a cross bar 9. This cross bar is pivotally engaged by an arm 10 extending from an eccentric strip 11 mounted on an eccentric 12. Said eccentric is secured to a 60 shaft 13 journaled in suitable bearings provided on the posts or standards 1 at one end of the machine. A pulley 14 is secured to said shaft and is adapted to receive motion through a belt 15 from a pulley 16 secured 65 to a transverse drive shaft 17 journaled upon said posts or standards 1 and which is adapted to be operated in any suitable manner.

Arranged transversely of the box 8 at the 70 bottom thereof are preferably three troughs indicated at 18, 19 and 20, respectively. The trough 18 is arranged between the downwardly converging bottom portions 21 and 22 of a hopper 23 extending inwardly from 75 one end of the box 8 and preferably overhanging the shaft 13 and the eccentric thereon. A deflecting lip 24 is extended downwardly from the upper end of the inclined portion 21 of the bottom of hopper 23 and 80 overhangs the middle trough 19. An imperforate incline 25 extends upwardly from that side of the trough 19 remote from the trough 18 and the upper end of this incline overhangs the third trough 20. Another incline 26 extends upwardly from that side of trough 20 remote from trough 19 and merges, at its upper end, into the bottom 85 27 of a discharge spout 28 within one end of the sieve box. The top of the discharge spout is preferably formed of a curved plate 29 secured upon the sides of the box and extending throughout the width 90 of the box.

By providing spaced troughs 18, 19 and 95 20 with the inclines extending from the troughs 19 and 20 and the hopper extending above the trough 18, it will be apparent that two air passages 30 and 31 are produced, the air passage 30 extending above 100 the trough 19 and incline 25, while the passage 31 extends above the trough 20 and incline 26. Supporting cleats 32 are secured to the inner faces of the sides of the box 8 at the upper end of passage 30. Additional 105 supporting cleats 33 are secured to the sides of the box 8 and at the upper end of the passage 31, these cleats 33 being disposed below the cleats 32. Additional supporting cleats 34 are secured to the sides of the 110 box 8 at the top of the hopper 23. These cleats 34 are preferably in substantially the

same plane as the cleats 32. Detachably mounted on the cleats 33 is the frame 35 carrying a screen fabric 36 of coarse mesh so as to permit coarse grits to pass there-through. This frame 35 is detachably mounted on the cleats 33 and the fabric 36 extends entirely across the passage 31 there being, however, a small outlet space between the upper end of the incline 26 and the outer end of the screen frame, as shown at 37. Longitudinal displacement of the screen frame 35 is prevented by blocks 38 secured to the sides of the box 8.

The inner end of the screen frame 35 abuts against the adjacent ends of the cleats 32 and is lapped by the frame 39 which carries a screen fabric 40 of sufficiently fine mesh to permit only fine grits to pass there-through. This screen fabric 40 extends across the upper end of the passage 30.

Extending entirely over the hopper 23 and resting on the cleats 34 is a frame 41 having superposed screens 42 through which meal is adapted to fall into the hopper 23. Material passing from the inner end of each of the screen fabrics 42 is adapted to be received by the screen fabric 40, there being a lip 43 extending from the discharge end of the fabric 42 and lapping the frame 39. The frame 39 is held against displacement in one direction by the frame 41 and in the other direction by blocks 44 secured to the sides of the box 8.

Extending over all of the screens and from one side to the other of the box is a frame 45 carrying a coarse fabric 46. This screen fabric 46 serves to prevent large particles of foreign substances from entering the separator.

Secured to the posts or standards 1 at the drive end of the machine is a blower casing 47, said casing being concentric with the shaft 17. The blower 48 is fastened to shaft 17. A flue 49 extends from the casing 47 and is forked near its upper end, one branch of the flue, which has been indicated at 50, being adapted to direct air into the passage 30 while the other branch 51 extends under the trough 19 and directs air into the passage 31. A bowed deflecting plate 52 is formed integral with the top wall of flue 49 and extends into the passage 30 close to and under the inclined portion 21 of hopper 23, while another bowed deflecting plate 53 is formed integral with the top wall of the branch 51 and extends into the passage 31 close to the incline 25. The flue 49 and its branches are not secured to the box 8 but are suitably supported by side connections 54 between the posts or standards 1, the deflecting plates 52 and 53 being held stationary while the box 8 is moved under the action of the eccentric 12.

A damper 55 is pivotally mounted at the fork of flue 49 and is adapted to be adjust-

ed angularly so as to regulate the discharge of air through the branch 50. This damper has an arm 56 movable therewith and said arm can be fastened in any desired manner so as to hold the damper 55 in any position to which it may be adjusted.

Each of the troughs 18, 19 and 20 has an outlet 57 extending therefrom at one end.

Extending under the screen 42 are oppositely disposed beaters or agitators 58 preferably though not necessarily, bowed as shown in Fig. 2 and having end portions journaled in the sides of the box 8. One end of each beater extends outwardly through the opening 6 in the main frame 80 and terminates in a crank arm 59 having an inturned end 60 pivotally engaging the enlarged portion 5 in which the opening 6 is formed. The crank arms 59 extend in opposite directions and it will be obvious that when the box 8 moves longitudinally relative to the side beams or connections 3, the beaters or agitators 58 will be caused to swing so as thus to tap upon the bottom of the screen 42 and loosen any material which may become lodged in the meshes of the screen.

In using the apparatus the shafts 17 and 13 are driven in any suitable manner so as to cause the blower 48 to revolve and the box 8 to reciprocate. Sufficient spaces are formed between the deflectors 52 and 53 and the inclines 21 and 25 respectively so that this relative movement will not be interfered with. After the parts have been set in motion the material to be separated is directed onto the screen 46 so as to pass therethrough onto the screens 42. At this point the meal contained in the material will be separated from the grit and bran and will gravitate into the hopper 23 from which it will pass by way of trough 18 to the spout 57 extending from said trough. The beaters constantly act upon the screen 42 so as to keep the meshes open, as before described. The grits and bran pass from the screen 42 onto the screen 40. At this point only a light current of air is directed against the material on screen 40, this being due to the fact that the damper 55 deflects most of the air current into the branch 51, Consequently while bran contained in the mixture will be blown upwardly from screen 40, the air current will not be sufficiently strong to prevent the fine grits from passing downwardly through the screen. These fine grits will fall onto the incline 25. The deflector 52 directs the air current transversely of the passage 30 so that it will strike the incline 25 and thus cause any bran which may pass through the screen 40, to be discharged upwardly along incline 25 and through the space formed between the upper end of said incline and the inner end of the frame 35. The coarse grits and bran

passing off of screen 40 will be discharged onto screen 36 and here met by a strong current of air passing from the branch 51 and through passage 31. Consequently, bran mixed with the coarse grits will be blown outwardly through the spout 28, while the coarse grits will gravitate onto the incline 26 and thence to the trough 20 from which they will be discharged through the spout 57 extending from said trough. The deflector 53 directs the current of air across passage 31 and against the incline 26 so that, should any bran fall through the screen 36, it will be met by this current and thrown outwardly through the space 37. By means of the damper 55 the relative velocities of the air currents discharged through the branches 50 and 51 can be varied.

It has been found that by utilizing the deflectors 52 and 53, any bran which may be adhering to the grits will be separated therefrom and blown from the machine.

What is claimed is:—

1. A separator including spaced inclines forming an air passage therebetween, means at the lower end of the incline for receiving material gravitating therealong, a screen extending across the upper end of the air passage, a flue discharging into the passage and having its lower wall leading to a point

close to the material receiving means, an arcuate deflecting plate constituting a continuation of the upper wall of the flue and overhanging the material receiving means 35 for directing air currents downwardly onto and upwardly along the incline, and means for directing an air current into the flue.

2. A separator including spaced inclines forming separate air passages therebetween, means at the lower end of each incline for receiving material gravitating therealong, screens extending across the upper ends of the air passages, a flue having branches discharging into the respective passages, the lower wall of each branch leading to points close to the respective material receiving means, arcuate deflecting plates constituting continuations of the upper walls of the branch flues and overhanging the respective material receiving means for directing air currents downwardly onto and upwardly along the respective inclines, and means for directing an air current into the flue and its branches.

In testimony that I claim the foregoing as my own, I have hereto affixed my signature in the presence of two witnesses.
